SYNCHRONIZING APPARATUS.

941,891.

Specification of Letters Patent.

Patented Nov. 30, 1909.

Application filed May 16, 1908. Serial No. 433,206.

To all whom it may concern:

Be it known that I, PIETRO PIERINI, a subject of the King of Italy, residing at No. 224 Via Cavour, in the city of Rome, Italy, have invented a new and useful Synchronizing Apparatus, of which the following is a specification.

The object of this invention is to provide an electro-mechanical apparatus for synchronizing automatically the movement of a kinematograph with that of one or more talking machines.

The apparatus devised by me to that purpose is formed essentially as follows:

15 A mechanical power imparts the movement, by means of a sufficiently slack belt, to a transmission-shaft on which are mounted a centrifugal regulator for actuating a brake, an electric current-distributer, and a gear 20 which, in its turn, transmits the movement by way of a rigid transmission, to the mechanism of a kinematograph. The belt sufficiently loose, being able to slip on the pulley mounted on the transmission-shaft, 25 allows the regulator to actuate the centrifugal brake and renders regular therefore the movement of the distributer, and consequently that of the kinematograph.

30 The distributer mounted on the transmission-shaft and fully described hereinafter, sends the electric current which may be supplied by any form of generator, successively and separately to the various sections of the magnetizing winding fitted on the stator of 35 an electro-magnetic brake. The rotor of the said electro-magnetic brake, energized by an electric current, is mounted upon a shaft coupled mechanically to that of the talking machine.

40 The talking machine is actuated by a source of power quite distinct from that which causes the rotation of the kinematograph, and preferably by the power derived from a clock-spring previously wound.

45 The rotor of the electro-magnetic brake being mounted on the shaft of the talking machine, which is generally moved by a tension spring, modifies when necessary the movement of the talking machine so as to 50 render it perfectly synchronous with that of the kinematograph. This action of the brake is automatic and uninterrupted. In this arrangement, therefore, three powers act: The first power (which may be of any kind whatever) impresses motion to the kinematograph and to a distributer; the second

power (which may be also of any kind, but preferably originated from a tension spring) actuates the talking machine; the third power originated by electricity energizes, 60 through the distributer, the electro-magnetic brake, which regulates automatically and without interruption the speed of the talking machine, rendering it synchronous with that of the kinematograph.

65 My invention is illustrated in the accompanying drawings, in which—

Figure 1 represents a diagram of the whole arrangement of devices and their connection. Fig. 2 is a plan showing in detail 70 the distributer, the electro-magnetic brake and their electric connection. Fig. 3 shows a modified arrangement of the distributer and its connection with the electro-magnetic brake.

75 In the upper part of Fig. 1 the following devices are grouped: A motor 1, by means of a belt 2, drives the transmission shaft 3, 4. On this shaft is mounted the distributer 5, on which the brushes 6 and 7 rest. These 80 brushes receive current from the electric power source 8. On the same shaft a centrifugal speed regulator 9 is mounted, which actuates a friction-brake 10, adjustable by means of screw 11. A pinion 12, mounted 85 on the said transmission shaft, meshes with wheel 13, which in its turn causes the sprocket wheel 14 to rotate and, thus transmitting by means of chain 15 the motion to the sprocket wheel 16, which actuates the 90 kinematograph 17. Belt 2 must be slack so as to allow the centrifugal brake to regulate the speed of the distributer and of the kinematograph. The distributer 5 has three 95 rings mounted on the transmission shaft 3, 4, and on which brushes 18, 19 and 20 rest. These brushes carry the electric current from 8 to the stator of the electro-magnetic brake 24. The rotor 25 of said brake is connected by means of shaft 26 to 100 the talking machine 27. This shaft is actuated by a spiral spring 28 contained in a drum 28 and which can be wound with a small key 29.

105 Fig. 2 shows in its upper part the distributer, consisting essentially of a metallic drum divided by means of longitudinal cuttings into three sections 30, 31 and 32, comprising three equal arcs and insulated from each other. These sections are electrically 110 connected with rings 33, 34 and 35, on which the three brushes 18, 19 rest respectively.

These three brushes are joined, through conductors 21, 22 and 23, to the terminals 36, 37 and 38 of the stator of the electro-magnetic brake. The windings of the stator start 5 from terminals 36, 37 and 38 and end at terminal 39. The electric current supplied by generator 8 is carried to the distributor by brushes 6 and 7 which rest on the drum of the distributor at diametrically opposite 10 points and, through brushes 18, 19 and 20, it is further carried to the three windings of the stator. The electric currents supplied by the distributor create in the iron ring 24 (stator) a magnetic flux which displaces 15 with a speed depending upon the distributor itself. In the method of connecting shown in Fig. 2, the current passes simultaneously through two of these three windings. Within stator 24 the rotor 25 is placed 20 concentrically and mounted upon shaft 26. The rotor consists of an iron wheel provided with pole tips on each of which are placed coils, every other coil being wound in the same direction. These coils form part of a 25 circuit ending in rings 40 and 41. The necessary current is carried to rings 40 and 41 by means of a couple of brushes 42 and 43.

Fig. 3 represents another method of connecting up the distributor. In this case 30 generator 8 carries the electric current directly to terminal 39, the joining point of the three windings of the stator, by means of a conductor connected with one pole of said generator; the other pole is put in connection with brush 6 on the drum of the distributor. All the rest remains as it is in Fig. 35 2. In this case, however, the electric current of the generator passes at a certain moment only through one winding of the rotor.

40 Let us now examine the working of the arrangement which is the object of this invention.

The mechanical regulator for the kinematograph insures the constant rotary speed of 45 the latter and of the distributor, which will be in a definite ratio to the speed of the shaft of the kinematograph. In consequence of the rotation of the distributor, the stator will be the seat of a rotary field, the direction of 50 rotation to be chosen so as to agree with that of the movement originating from the spring which actuates the shaft 26, such shaft being common to the rotor 25 of the brake and to the talking machine. This 55 having been settled, we may disregard the kinematograph, as its rotary speed is made to be uniform by the special mechanical device and is controlled by screw 11, so as to fit the scene or subject to be taken or reproduced. We must, therefore, only consider 60 how to regulate the speed of the talking machine 27, so that it may be kept in a definite numerical ratio to that of the kinematograph, so that the movement of these two 65 apparatuses and consequently the movement

of the film and of the record may be made synchronous, and caused to remain so. This result is obtained by the electro-magnetic brake annexed to the talking machine, the action of such brake tending to accelerate 70 the speed of the talking machine whenever such speed is below that required for synchronizing and tending to retard it in the contrary case. Indeed the resisting couple of the rotor of the said brake proves to be 75 (the speed of the rotary field of the stator being equal, as well as its intensity) proportionate to the speed of the rotor and therefore also to the rotary speed of the talking machine. The said couple opposing the acceleration of the spring will cause first a constant or uniform speed for the talking machine, which we shall take as synchronous speed, and furthermore will tend to compensate automatically and immediately, by 80 means of variations in its own intensity, any casual variations of the said synchronous speed.

The practical use of the apparatus, the nature and working of which I have explained requires small consumption of electric power (the regulator only acting as a brake). To make the apparatus work it is sufficient to establish an initial correspondence between the kinematographic film and 95 the gramophone record, which can be effected in any suitable manner.

I claim:

1. The combination with a kinematograph and a talking machine, of apparatus for effecting their synchronous operation comprising separate motors for the kinematograph, and for the talking machine, a transmission device for said kinematograph and automatic means controlled by the movement of 100 the transmission device of said kinematograph for controlling the speed of the talking machine.

2. The combination with a kinematograph and a talking machine, of apparatus for effecting their synchronous operation comprising separate motors for the kinematograph and for the talking machine, a transmission device for said kinematograph and an electro-magnetic brake for said talking machine, 110 said brake being controlled by the movement of the transmission device of said kinematograph.

3. The combination with a kinematograph and a talking machine, of apparatus for effecting their synchronous operation comprising separate motors for the kinematograph and for the talking machine, a transmission device for said kinematograph, a current distributor carried by said transmission device 115 and an electro-magnetic brake controlled by said current distributor for checking the speed of the talking machine.

4. In an apparatus for synchronizing the operation of a kinematograph and a talking 130

machine, a motor for said kinematograph, a transmission shaft and distributer, and a centrifugal brake on said transmission shaft, a motor for said talking machine, an electro-
5 magnetic brake for retarding the movement of the talking machine motor, and an electrical connection between said electro-mag- netic brake and said distributer whereby the brake is controlled by the distributer.

PIETRO PIERINI.
